US00D401914S

United States Patent [19]

Kamegi

[11] Patent Number: **Des. 401,914**
 [45] Date of Patent: ****Dec. 1, 1998**

[54] **PORTRABLE INFORMATION TERMINAL UNIT**

918511 2/1995 Japan .
 982633 6/1997 Japan .

[75] Inventor: **Mikio Kamegi**, Kawasaki, Japan

[73] Assignee: **Kabushiki Kaisha Toshiba**, Kawasaki, Japan

[**] Term: **14 Years**

[21] Appl. No.: **75,539**

[22] Filed: **Sep. 2, 1997**

[30] **Foreign Application Priority Data**

May 7, 1997 [JP] Japan 9-53504
